UNITED STATES PATENT OFFICE

CHARLES EDMUND BEALE, OF LONDON, ENGLAND, ASSIGNOR TO ASSOCIATED TELEPHONE AND TELEGRAPH COMPANY, OF KANSAS CITY, MISSOURI, A CORPORATION OF DELAWARE

TELEPHONE SYSTEM

Application filed October 1, 1928, Serial No. 309,649, and in Great Britain November 23, 1927.

The present invention relates to telephone systems and is more particularly concerned with systems employing switches of the so-called "drop back" type, that is, switches which automatically return to normal upon receipt of a digit of critical value. While the invention has also wider application, its use is particularly advantageous in a private branch exchange system employing 100, or 200-point switches, and comprising in the first case 100 lines or less, and in the second case comprising 200 lines or less. It is well established practice in telephone systems of all sizes that the dialling of the single digit "0" shall secure connection with an operator but in systems using 100 point switches, for example, this has generally involved the setting aside of the "0" level for connections to operators, and this necessitates the use of an additional rank of switches in order to give full hundred line capacity. This, in the particular case of an exchange of from 90-100 lines may be a serious drawback, and it is one object of the invention to provide an arrangement whereby the full capacity of the switch bank may be retained while still adhering to the accepted practice of employing the dialling of "0" to obtain connection with an operator.

According to the invention, connection is obtained with an operator by dialling "0", but not over the "0" level of the drop back switch, and connections with the contacts in the "0" level may be made by dialling "0" after the switch has dropped back in response to the dialling of a particular critical digit.

The invention will be better understood from the following methods of carrying it into effect, reference being had to the accompanying drawings, comprising Figs. 1, 2 and 3.

Fig. 1 shows a 100-point switch and Fig. 2 a 200-point switch and it will be understood that a number of detailed modifications can be made by those skilled in the art without departing from the spirit of the invention. Fig. 3 a subscriber's station T and associated lineswitch LS which has ac-

cess to the switches of Figs. 1 and 2. The subscriber's lines are multipled to jacks, such as J, at the operator's position.

Referring more particularly to Fig. 1, a circuit of a 100-point final selector or connector switch is shown of substantially known type, arranged, however, to be released on the receipt of a particular critical digit, while if that digit is dialled a second time the switch is not again released. The actual value of the digit dialled is immaterial, and for the sake of example, it will be assumed that it is 6. If the system is assumed to comprise 100 lines, the subscribers will in every case dial three digits, the first of which will be 6, but only a single rank of 100-point switches will be required. In order to obtain access to the operator, however, the single digit "0" will be dialled.

When a subscriber initiates a call by removing his receiver, his lineswitch LS will operate in the well known manner to seize a free connector switch, which it will be assumed is that shown in Fig. 1. In response thereto, relay A will operate and the subscriber will receive dial tone from the dial tone conductor DT, over normally closed post springs NP3, make-before-break springs controlled by armature 115 of relay R, lower winding of relay A to the lower speaking conductor. Relay A at armature 101 completes a circuit for release relay B which energizes and at armature 105 earths the release trunk conductor 130, at armature 103 earths the motor start lead 129, at armature 104 completes a circuit for the lamp P. G. over the normally closed off-normal springs ONS, and at armature 106 prepares the impulsive circuits in the usual manner.

The calling subscriber now proceeds to dial the digit 6, whereupon six impulses are transmitted to the vertical magnet VM over the slow acting series relay C. Relay C energizes and remains operated throughout the digit and at armature 108 completes an alternate impulsive circuit over the operated off-normal springs, the lamp P. G. at this time being extinguished due to the opening of the off-normal springs. In response to the operation of the vertical magnet, the

wipers are stepped up to the sixth level, and on this level post springs NP1 close. Accordingly, when relay C falls back, a circuit is completed for the lower winding of relay 5 R as follows: earth, armature 104 and front contact, armature 113 and back contact, operated post springs NP1, back contact and armature 107 of relay C, lower winding of relay R to battery, a parallel circuit being 10 completed for release magnet Z over front contact and armature 102 of impulsing relay A, operated off-normal springs, release magnet Z to battery. Relay R is a two-step relay and at this time operates its light-tensioned armature 114 only, thereby short-circuiting its upper winding over armature 113, post springs NP1 and armature 107. Release magnet Z, however, now operates 15 and the switch is returned to normal in the usual manner, whereupon post springs NP1 open, removing the short-circuit from the upper winding of relay R, which relay now operates fully over both its windings in series and locks energized over its light-tensioned armature 114 to earth on armature 20 104. Relay R at armature 115 operates the make-before-break springs and disconnects dial tone from the lower winding of relay A, connecting in place thereof direct earth. 25

The calling subscriber will now proceed to dial the two digits of the wanted party, and it will be assumed that the first of these digits is again 6. The post springs NP1 will operate on the 6th level as before, but 30 this is without effect at this time as the initial energizing circuit of relay R is opened at armature 113. Consequently, the wipers remain opposite the 6th level into which they are operated in response to the 35 dialing of the final digit, the operations during and subsequent to the dialing of this digit are well known and need not be described at this time.

In connection with the release of the 40 switch, however, it may be noted that if the strap 120 is connected up, last-party release of the connector will be secured, while if the strap is left disconnected release will be under the control of the calling party. In 45 the former case it will be seen that release relay B is held energized, as long as the called party is on the line, in the circuit extending from earth, front contact and armature 103, armature 109 and front contact of back-bridge relay D, strap 120, winding of relay B to battery, while in the latter case relay B releases a short interval after the release of relay A.

Considering now the case in which the 50 calling subscriber desires to obtain connections to an operator, and accordingly dials the digit "0" in the usual manner. In this case, post springs NP2 are operated, and a circuit is completed from earth over armature 115 and back contact of relay R, oper-

ated post spring NP2 to the calling lamp lead 131 extending to the operator's position, over a wiper of the line switch. In addition, the post springs NP3 are operated on this level, so that dial tone is disconnected 70 from the lower speaking conductor and ringing tone is connected up, to indicate to the calling party that the operator is being signalled.

The lighting of lamp L informs the operator that a call is waiting and she plugs one end of a cord circuit (not shown) into multiple jack J of the calling subscriber's line. Relay 305 operates in a circuit extending from battery in the cord circuit, sleeve 75 of jack J, winding of relay 305, to ground, and at armatures 307 and 308 opens the line extending to the automatic switches, which thereupon release. It will be clear that if the subscriber first dials the critical digit 6 80 and then the digit 0 followed by a further digit he will be able to obtain access to any subscriber whose line terminates in the 0 level, since in the case of a call to an operator the switch does not cut in on this level 85 and the connection to the operator's position is not actually made over the wipers of the switch.

Referring now to the accompanying drawings, designated Fig. 2, which shows a modification of the invention as applied to a 90 200-point connector it will be seen that the circuit arrangement of this switch is substantially the same as that of the 100-point connector illustrated in Fig. 1, with the exception that two re-setting relays R1 and R2 are provided instead of the single relay R, these two relays acting as auxiliary switching relays to connect up one set of wipers or the other according as to whether 95 the call is for a subscriber in the first hundred bank or the second hundred bank. In this modification, the switch is adapted to respond to two critical digits, their value being immaterial, the choice of the digits 100 being quite arbitrary, and for the sake of example it will be assumed that in order to obtain connection to a subscriber whose line terminates in one of the first hundred group of bank contacts, the digit is 6, the subscriber dialling this digit in every case, followed by the two digits of the subscriber's 105 line, while in order to obtain connection to a subscriber whose line terminates in the second hundred group of bank contacts the digit is 8, the calling subscriber in each case 110 dialling this digit followed by the two digits of the wanted party.

In the initiation of a call, assuming that it is for a subscriber in the first hundred bank, the line relay A will operate in the usual manner, and at armature 201 complete a circuit for release relay B. Relay B operates and at armature 205 earths the release 115 trunk conductor 130', at armature 204 pre- 120

5 pares circuits for the re-setting relays R1 and R2, and release magnet Z, and at armature prepares 206 prepares impulsing circuits in the usual manner.

10 The subscriber now proceeds to dial the digit 6, whereupon six impulses are sent to the vertical magnet VM over the slow-acting series relay C. Relay C operates and remains operated throughout the transmission of the digit, at armature 208 relay C opens a point in the circuit of relays R1 and R2 and release magnet Z, and at armature 209 completes an alternative impulsing circuit extending over the now operated off-normal 15 springs ONS. When the wipers are stepped up to the 6th level, post springs NP1 operate and when relay C releases a circuit is completed for relay R1 as follows: earth, armature 204 and front contact, armature 208 and back contact, armatures 230 and 236 and their back contacts, operated contacts of post springs NP1, normally closed contacts of post springs NP2, back contact and armature 238, the lower winding of relay R1 20 to battery, and in parallel thereto over armature 207 and front contact, operated off-normal springs, release magnet Z to battery. Relay R1 is a two-step relay and first operates its light-tensioned armature 237, 25 thereby short-circuiting its upper winding in the circuit extending from the left-hand terminal of the upper winding of relay R1, front contact and armature 237, armature 208 and back contact, armatures 230, 236 and their back contacts, operated contacts of post springs NP1, normal contacts of post springs NP2, back contact and armature 238, to the right-hand terminal of the upper winding of relay R1. Release magnet Z, 30 however, operates and the switch is released in the usual manner, whereupon post springs NP1 return to normal and remove the short-circuit from the upper winding of relay R1 so that relay R1 operates fully over 35 both its windings in series, and locks up to earth on armature 204 over its light-tensioned armature 237.

40 If now the calling subscriber again dials the digit 6, the wipers will be stepped up to the sixth level in the usual manner, but will have no effect on the operation of the re-setting relays as relay R1 has opened the initial energizing circuit for both relays R1 and R2. Relay R1 when fully operated, at 45 armatures 234, 235 and 239, connects up the wipers 243, 244 and 245 to the normally open contacts of the switching relay H. The subscriber now proceeds to dial the digits in the wanted party's number, and 50 the operation of the switch including the operation of the ringing trip relay F, the test relay E and the busy relay G in the well-known manner during and subsequent to the dialling of these digits are standard 55 and need no further description.

If now the calling subscriber desires to obtain access to a subscriber whose line terminates in the second hundred bank, he will in every case first dial the digit 8, the switch will step its wipers up to the 8th level in the usual manner and post springs NP2 will operate. On the release of relay C a circuit will be completed for relay R2, and for the release magnet Z in a similar manner to that described for the operation of relay R1. Relay R2 first operates its light-tensioned armature 231, thereby short-circuiting its upper winding, and on the release of the switch when relay C releases at the end of the digit, under the control of the release magnet Z the post springs NP2 return to normal removing the short-circuit from the upper winding of relay R2, and allowing this relay to operate fully over both its windings in series. Relay R2 at armature 230 opens the initial energizing circuit for both relays R1 and R2 so that if the digit 8 is again dialled, the wipers will be stepped up to the 8th level and can be rotated into that level on receipt of the final digit. Relay R2 at armatures 228, 229 and 233 connects up the wipers 240, 241, and 242 to the normally open contacts controlled by the switching relay H. The operation of the switch during and subsequent to the dialling of the two final digits is as before well known and needs no further description.

In case connection to the operator is desired, the calling subscriber dials the single digit "0." When the switch is operated to the tenth level, normal post springs NP3 operate and close a circuit from ground at the resting contact of armature 251 and said armature, resting contact of armature 250 and said armature, normal post springs NP3, conductor 131', conductor 131 (Fig. 3), bank contact and wiper 309 of line-switch LS, conductor 310, lamp L, to battery. Lamp L lights to inform the operator of the call and the connection to the automatic switches is released as soon as the operator answers the call, in the same manner as previously described in connection with Figs. 1 and 3.

What I claim as new and desire to secure by Letters Patent is:—

1. In a telephone system, an automatic switch, an operator's position, means for operating said switch responsive to digit impulses, means responsive to a predetermined first digit for signalling said operator's position, and means responsive to a different predetermined first digit for automatically releasing said switch and rendering said signalling means ineffective in case the said first predetermined digit is then called.

2. In a telephone system, an operator's position, an automatic switch, means responsive to a particular digit for operating said

70

75

125

130

switch to a particular position, and means responsive to said operation for either signalling said operator's position or for preparing said switch for further operation dependent on whether said digit was the first or was preceded by a different predetermined digit.

3. In a telephone system, an operator's position, an automatic switch, means responsive to a predetermined digit for operating said switch to a particular position, means for signalling said operator's position if said digit is the initial digit of a series, and means for rendering said last means ineffective if said digit is preceded by a different predetermined digit.

4. In a telephone system, an automatic switch having access to subscribers' lines through wipers on said switch, an operator's position, means responsive to a predetermined digit for operating said switch to a particular position, means effective if said digit is the first of a series for signalling said operator's position independently of said wipers, and means effective if said digit is preceded by a different predetermined digit for partially operating said switch to connect with one of said subscribers' lines and for rendering said signalling means ineffective.

5. In a telephone system, an automatic switch having wipers, a pair of talking conductors in said switch, means for operating said switch responsive to received digit impulses, means responsive to the receipt of a predetermined first digit for automatically returning said switch to normal, and means responsive to the release of said switch for connecting said talking conductors to said wipers, said means being effective only if said digit is the first received.

6. In a telephone system, an automatic switch having a plurality of sets of wipers, a pair of talking conductors in said switch, means for operating said switch responsive to received digit impulses, means responsive to the receipt of a predetermined digit for automatically returning said switch to normal, and means responsive to said last means for connecting said talking conductors to a particular one of said sets of wipers depending upon the value of said predetermined digit.

7. In a telephone system, an automatic switch having wipers, a pair of talking conductors in said switch, means responsive to a predetermined initial digit for operating said switch to a particular position, a two step relay in said switch, means responsive to said operation for partially operating said relay and for releasing said switch, and means responsive to said release for fully operating said relay to connect said talking conductors to said wipers.

8. In an automatic switch, a pair of talk-

ing conductors, two sets of wipers, a pair of two-step relays for connecting said talking conductors to said two sets of wipers respectively, means for operating said switch responsive to receive digit impulses, means responsive to a predetermined initial digit for partially operating the first of said relays and for releasing said switch, means responsive to a different predetermined initial digit for partially operating the second of said relays and for releasing said switch, and means responsive to the release of said switch for fully operating the partially operated relay to connect said talking conductors to the associated set of wipers.

9. In a telephone system, an operator's position, a two motion ten-level connector switch, means for operating said switch responsive to received digit impulses, means responsive to a received digit corresponding to a particular level of said switch for signalling said operator's position, and a group of ten subscribers' lines accessible to said connector in said particular level.

10. In a private automatic exchange employing line switches and two-motion directive connector switches, multiple connector banks comprising contacts arranged in ten groups with ten sets of contacts in each group, said banks being fully equipped with one hundred subscribers' lines, an operator's position, and means responsive to the operation of one of said connectors to a position corresponding to a particular one of said groups for signalling said operator's position.

11. In a private automatic exchange employing line switches and two-motion directive connector switches, multiple connector banks comprising contacts arranged in ten groups with ten sets of contacts in each group, said banks being fully equipped with one hundred subscribers' lines, an operator's position, and means responsive to the operation of one of said connectors to a position opposite a particular one of said groups for either signalling said operator's position or partially completing a connection to one of said subscribers' lines dependent upon whether or not said operation was preceded by a preliminary operation of the connector.

In testimony whereof I have signed at Liverpool, England, this 7th day of September, 1928.

CHARLES EDMUND BEALE.
